OIL CAN

Filed Oct. 11, 1928

F. C. Lindsey,
INVENTOR.

BY *Sterling P. Buck,*
ATTORNEY.

UNITED STATES PATENT OFFICE

FREDERICK CROCKER LINDSEY, OF MILWAUKEE, WISCONSIN

OIL CAN

Application filed October 11, 1928. Serial No. 311,938.

This invention relates to oil cans, and more specifically, to an improved oil can or oiler by means of which lubricating oil can be forced upward through the oiling spout.

5 In applying oil to machinery, there are many parts which need lubrication and which are not accessible by means of an ordinary oil can or oiler, by reason of the fact that some superposed or overhanging part of the machine interferes.

10 Therefore, the main object of this invention is to provide an oil can or oiler which, while being operated as any of the regular or standard oilers, will act as a force pump, for forcing the oil upward, so that such comparatively inaccessible parts of the machinery can be conveniently and easily reached by the oil-can-spout while it is in its effective position for applying oil, by forcing the oil upward 20 through the oil-can-spout.

Another object of this invention is to provide a device of this character which is comparatively simple, capable of being manufactured at a reasonable cost, and which does 25 not sacrifice any of the good qualities of the oilers now in general use.

Other objects and important features are pointed out or implied in the following details of description, in connection with the accompanying drawings, in which:

Figure 1 is a side elevation of one of my improved oil cans in a position for being operated to force the oil upward, the internal parts being shown in dotted lines.

35 Figure 2 is a central sectional view through the middle of the oil-can-spout and feeding pipe, united with a part of the closing cap of the oil can.

Figure 3 is a bottom plan view of the closing cap and the parts which are united therewith.

40 Figure 4 is an enlarged central sectional view illustrating the construction of the closing cap and the check-valve, the oiling spout being omitted, a fragment of the body or container being also shown in this view.

Referring to these drawings in detail, in which similar reference characters correspond to similar parts in the several views, 45 and in which the body or container 5 is of the

usual form in which the bottom 6 is downwardly bulged and upwardly depressable, it will be seen that the screw-cap has the usual threaded engagement with the filling opening, as indicated at 7, and that the usual ring or gasket 8 prevents leakage between the container 5 and the rim of the screw cap which is indicated at 9. This screw cap is centrally apertured, as shown at 10, and the oiling spout 11 extends through this opening 10. A feeding pipe or channel 12 is connected to the spout 11 at or adjacent to the opening 10. As shown in Figure 2, the part 12 extends into the lower end of the spout 11, and these parts 10 and 11 are preferably soldered to one another and to the bottom of the screw cap 9 by solder or other appropriate means, as indicated at 13. The feeding pipe 12 extends at an angle to the oiling spout 11, and its lower end terminates at a point near the periphery of the bottom 6. The feeding spout is sufficiently capacious to hold a considerable amount of oil, and to freely feed the oil into the spout 11 without unnecessary retardation, while its lower end is partially closed either by a cap such as shown in Figure 2, or by other appropriate means, and is provided with a relatively small opening 14 through which the oil can be forced in a manner which will presently be explained.

45 An air inlet member or tube 15 has its upper end closed, and has air inlets 16 near its closed upper end. The lower end of this tube 15 is normally closed by means of a spring-valve 17, but capable of being opened by a downward movement of the contiguous end of the spring-valve, the latter being secured to the bottom of the screw-cap, by solder or other appropriate means, at 18. This spring-valve is preferably of the shape shown in Figure 3, 50 that is, substantially semi-circular, so it will not be interfered with by the feeding tube 12. This spring-valve is preferably of very thin, flexible and elastic metal, and fits snugly against the lower end of the air inlet pipe 15 in consequence of its spring action. The tube 15 extends through an eccentric opening 19, and may be secured therein by solder or other appropriate means, as indicated at 20. The purpose of having the upper end of the pipe 55

15 closed, is to prevent metal shavings, dirt and other objectionable matter from falling into the oil can, while the air inlets 16 admit air which is used to force the oil through the feeding pipe 12 and spout 11.

5 The operation of this oil can is as follows:

Naturally, the user holds the oil can with the curved end of the spout in the position shown in Figure 1, but even if the spout is 10 not curved, the operative position is indicated by the tube 15 which is always at the upper side. In other words, the lower end of the feeding tube is diametrically opposite to the side having the tube 15, and by keeping this 15 tube 15 at the top, it is known that the feeding pipe 12 is extending downward. Of course the oil gravitates to the lowest point, and as long as there is a very small quantity of oil in the container, the lower end of the 20 feeding pipe is surrounded by the oil. Therefore, when the bottom 6 is pressed inward, the valve prevents the oil or air from escaping through the tube 15, so some of the oil is forced upward into or through the feeding 25 pipe 12. When the pressure of the thumb or finger is released from the bottom 6, it returns to its normal position, and causes a partial vacuum to draw air in through the tube 15. This return of the bottom 6 and intake of air occurs very quickly, while the oil 30 tends to return through the opening 14 very sluggishly, because of the comparative smallness of this opening and the comparatively slight pressure or weight of the oil in the 35 pipe 12. Therefore, if the bottom 6 is depressed and released in rapid succession, the oil will accumulate in the feeding pipe and oiling tube until the latter overflows into or onto the part of the machine where the 40 oil is intended to be applied.

It is obvious that this oil can is not only useful for forcing the oil upward, but also for applying the oil while the oiling spout is extending downward. In this latter use of the 45 oil can, it is particularly useful in preventing the oil from being used in excess, for the opening 14, as previously explained, causes the oil to flow sluggishly through the feeding tube, and when the oil can is inverted, the 50 normally lower end of the tube (which has the opening 14 therein) is above the level of the oil in the container, so the contents of the feeding pipe and oiling spout is relieved from the weight of the greater part of the oil in the 55 container.

Although I have described this embodiment of my invention very specifically, it is not my intention to limit my patent protection to these exact details of construction and arrangement, for changes may be made within the scope of the inventive ideas as implied and claimed.

What I claim as my invention is:

60 1. An oiler comprising a container having a springy part that is inwardly compressible

and which retracts by its spring action, an air-inlet, a spring-valve normally closing said air-inlet and preventing the exit of air therethrough, an oiling spout communicating with the interior of said container, and an oil feeding tube united with the inner end of the oiling spout and forming an inward extension thereof and extending to a point near the periphery of the container's bottom and having a restricted opening at its inner end, substantially as described, for the purposes specified.

70 2. The structure defined by claim 1, the said air-inlet being at the opposite side of the oiling spout from the said inner end of the 80 feeding tube, for the purpose specified.

75 3. An oiler comprising a container provided with a springy part adapted to be pressed inward and to retract by its spring action and thereby tend to create a partial 85 vacuum, said container having an oil-receiving opening, a removable cap normally sealing said opening and provided with an opening an oiling spout that communicates with the interior of the container through said 90 opening in said cap, an air-inlet through which air is drawn into the container by depressing and releasing said springy part, a spring-valve to close said air-inlet and prevent exit of air therethrough, and a feeding 95 pipe united with the inner end of the oiling spout so as to form an inward extension thereof and extending to a point near the periphery of the container's bottom and having a restricted inlet, substantially as shown, 100 for the purposes specified.

105 In testimony whereof I affix my signature.
FREDERICK CROCKER LINDSEY.
